CAP RETAINER

Joseph Farrelly, Pelham, N. Y.

Application December 11, 1935, Serial No. 53,853

1 Claim. (Cl. 221—60)

The invention relates to means for shackling a screw cap to a container so that said cap is retained against possible loss, and in accessible position for replacement when unscrewed.

5 One object of the present invention is to provide a cap retainer which is simple and inexpensive, which may be very easily attached to a container and a cap without any substantial change in the standard or existing forms of these 10 members, and which does not interfere with the easy and free finger rotative manipulation of the cap.

Various other objects, features and advantages 15 of the invention will be apparent from the following particular description and from an inspection of the accompanying drawing in which:—

Fig. 1 is a perspective view of a form of cap retainer, and

20 Fig. 2 is a vertical section of a fragment of a collapsible tube, on which is threaded a cap to which is applied the retainer of Fig. 1.

In the drawing there is shown a container 25 which is in the form of a collapsible tube 10 for shaving cream, dental cream and the like, and which has the usual threaded neck 11 adapted to receive a cap 12. In order to prevent loss 30 of the cap 12 through misplacement during the use of the collapsible tube 10, I provide a retainer 13 for shackling said cap to said tube.

The retainer 13 is made of a single length 35 of wire welded together at the ends and bent into shape to form two opposed C-shaped yokes 14, and a pair of loops 15 which are intermediate of said yokes, and which serve as springs for the retainer. The retainer 13 is attached to the container 10 and the cap 12, so that the spring loops 15 are disposed between the yokes 14 when in closure position.

40 In order to receive one of the retainer yokes

14, the neck 11 of the container is provided with a retaining peripheral groove 17. The cap 12 is annularly provided with a retaining groove 18 for receiving the other retainer yoke 14. The yokes 14 may be easily resiliently deformed into 5 snap engagement with the retainer grooves 17 and 18 respectively, and the retainer 13 will be secured in said grooves while permitting the cap 12 to be rotated into open or closed position. Upon loosening of the cap 12, said cap will spring 10 away from the discharge opening of the tube 10 into position to permit free discharge of the material from said tube without interference or contamination with the cap 12. In this sense, the spring loops 15 serve as hinges about which 15 the cap swings away from the discharge opening of the tube 12, or swings into closure position for replacement on the tube.

It is seen that in this construction, the retainer is made from a single piece of resilient 20 material, that it can be easily applied to a container or container cap by a simple snapping action, that it does not require any change in the construction of the container and its cap except for the provision of retainer grooves or tapered 25 surfaces, and that it does not interfere with the free and easy manipulation of the cap, the entire periphery of the upper portion of the cap which is gripped for manipulation being entirely free from any encumbrances. 30

Having thus described my invention, what I claim as new and desire to secure by Letters Patent is:—

A cap retainer made from a single length of wire and bent to form a pair of C-shaped yokes 35 open on their outer sides and interconnected by two parallel sections of said wire convoluted to form a pair of spring loops between said yokes.

JOSEPH FARRELLY. 40
